UNITED STATES PATENT OFFICE.

JOHN B. GORRELL, OF KENDALLVILLE, INDIANA.

SEMAPHORE SWITCH-SIGNAL.

1,158,482.

Specification of Letters Patent.

Patented Nov. 2, 1915.

Application filed August 31, 1914. Serial No. 859,474.

To all whom it may concern:

Be it known that I, JOHN B. GORRELL, citizen of the United States, residing at Kendallville, in the county of Noble and 5 State of Indiana, have invented certain new and useful Improvements in Semaphore Switch-Signals; and I do declare the following to be a full, clear, and exact description of the invention; such as will enable 0 others skilled in the art to which it appertains to make and use the same.

My invention relates to improvements in semaphore signals used in connection with railway switch throwing devices and has 5 for its object to provide a device in which the shape of a pair of blades becomes the distinguishing feature by means of which the position of the switch may be ascertained, rather than providing a device in 10 which the colors of the blades are the distinguishing features.

In carrying out the above end, a further object of the invention is to construct the device in the most simple manner consistent with its proper operation and to provide each blade with a border colored differently from its body, whereby the shape of said blade may be readily ascertained at a glance.

With the above and minor objects in view the invention resides in certain novel features of construction, combination herein described and claimed and shown in the drawings wherein:

Figure 1 is a side elevation showing the application of my invention to a switch throwing device, the position of the semaphore displaying the fact that the switch is closed; Fig. 2 is a similar view showing the position of parts when the switch is opened; and Fig. 3 is a horizontal section taken on the line 3—3 of Fig. 1.

In the accompanying drawings, I have shown a switch throwing device D which includes a combined switch throwing and locking lever L and an upright shaft S rising from the device and designed to rotate throughout an arc of 90° when the lever L is thrown from the position shown in Fig. 1 to that disclosed in Fig. 2.

Although the shaft S might well be rectangular throughout its length, its intermediate portion is preferably rounded as indicated at I. Secured to one of the flat sides of the shaft S near its upper end, is an upright vertically elongated semaphore blade

1 which is provided with an upright slot 2 offset from the line of the shaft and having its inner wall alined with the flat side of said shaft which is located directly at right angles to the side upon which the blade 1 is secured. The slot 2 is designed for the reception of a transverse horizontally elongated semaphore blade 3 which is secured to the adjacent portion of the shaft S by bolts 4 or other suitable fasteners, the blade 1 being likewise secured in position by similar fasteners 5.

When the lever L is swung to the position shown in Fig. 1, in which position the switch is closed, the upright blade 1 will be displayed to the engineer of an approaching train thus indicating the closed position of the switch while, on the other hand, when said lever is turned to the position seen in Fig. 2, thereby opening the switch, the horizontal blade 3 will be displayed. It will therefore be seen that the condition of the switch is ascertained by the shape of the semaphore blades rather than by the color thereof as is usual with devices of this character. By this means, it will be seen that a color blind operator of an approaching train would not fail to notice the condition of the switch as displayed by the semaphore. This is an extremely important feature.

In most cases, I intend to provide each blade with a surrounding border 6 which is colored differently from its body portion, the border being preferably dark while it is usually desirable to have the bodies of said blades coated with a light coloring material. By this means, should the semaphore be positioned at a rather dark point adjacent the track, the light body portion of the blades will clearly distinguish their shape, whereas, if the device is employed at a point at which the light is extremely strong, the dark border will clearly display the shape of the blade or panel.

I am aware that the mere provision of a differently colored border on the semaphore blade would not generally be termed mechanical invention but it will be understood, that since the shape of the blade is the important feature in the present case, and the border clearly distinguishes the shape of said blades, this feature seems to possess novelty as a mechanical structure.

Having thus described my invention what

2
I claim as new and desire to secure by Letters Patent is:

The combination with an upright rectangular shaft adapted to be rotated throughout an angle of ninety degrees, of an upright vertically elongated rectangular blade, contacting at its upright center with one flat side of said shaft, and having an upright rectangular slot whose inner wall 5 lies flush with an adjoining flat face of the shaft, and whose upper and lower ends are spaced equi-distantly from the upper and lower ends of the blade, bolts passing through the blade and the shaft, an addi- 10

tional and horizontally elongated rectangular blade inserted through the aforesaid slot, contacting with the walls thereof, and likewise contacting at its upright center with the shaft, and additional bolts passing through the aforesaid horizontally elongated 15 20 blade and through the shaft.

In testimony whereof I have hereunto set my hand in presence of two subscribing witnesses.

JOHN B. GORRELL.
